ART OF RECTIFICATION

Application filed February 9, 1929. Serial No. 338,811.

This invention relates to the art of rectification and bubbler plate columns, particularly to a special tray and liquid overflow construction and mode of operation.

In most distillation and rectification processes the condensate mixtures involved are completely homogeneous and miscible in all proportion at the temperatures existing in the rectifying column. In such processes the vapors rising through the liquid on the trays of the column come into contact with constantly changing concentrations on the trays, depending on the temperature gradient and number of trays in the column. Some liquid mixtures, however, do not remain completely miscible in the various proportions in which they occur in a rectifying column but separate into two layers on at least some of the trays. When this condition occurs in the ordinary column the upper layer on a particular tray overflows first and becomes a mere film on the surface of the lower heavier layer.

Under these conditions, an abnormal condition is created in the column since the tray or trays on which the liquids separate do not contain the proportions of the liquids which would normally condense and be maintained thereon as in the case where the liquids are completely miscible.

Therefore the present invention has as its primary object the provision of a method and a structure particularly adapted to overcome these difficulties, in accordance with which the invention comprises a bubble plate column in which means are provided for maintaining on each tray considerable portions of two immiscible liquids which may separate thereon.

The invention includes other objects and advantages which will be apparent from the following description taken in connection with the accompanying drawings in which:

Fig. 1 is a broken vertical sectional view of a portion of a bubbler tower showing a single tray embodying the features of the invention;

Fig. 2 is a horizontal sectional view of Fig. 1 looking down upon the line 2-2;

Figs. 3 and 4 are views similar to Fig. 1 showing modified forms of the overflow mechanism shown in Fig. 1; and

Fig. 5 is a diagrammatic view of a complete bubble tower with parts broken away to show the application of the apparatus according to one modification of the present invention.

Referring to Figs. 1 and 2 of the drawings, the numeral 2 represents a portion of a side wall of a bubbler plate column of the type used for the rectification of vapors, and 4 one of a series of vertically arranged bubble trays mounted therein. This bubble plate or tray 4 is provided with conventional bubble caps one of which is shown at 6. Each tray is provided with a condensate overflow pipe 8 which delivers the condensate from one tray to the next lower tray in the column.

The present invention is more particularly concerned with certain improvements in the method and means for regulating the flow of liquid from one tray to another by means of the pipes 8.

In the treatment of mixed vapors which condense to form two immiscible liquids on the trays of a bubble column the lighter liquid layer overflows first so that only a film is left on the tray. In order to secure proper rectification and intimate contact with both liquids in the proportion in which they are condensed the present apparatus includes an additional overflow band or pipe section 10 which is spaced from and around the upper part of the overflow pipe 8 as shown in Fig. 1. The band 10 may be supported in any convenient manner such for example as by slotted brackets 12 attached to the pipe 8. These brackets together with the necessary bolts hold the band 10 in the desired position so that the heavier liquid flows under the band 10 and directly into the pipe 8 while the lighter liquid is held to a higher level by the band, over which it then flows into the overflow pipe 8.

The slots in the supporting brackets 12 permit of a ready adjustment of the height of the band 10 above the top of the pipe 8 so that the relative amounts of the two liquids on each tray can be controlled in substantial accordance with the amount of each liquid condensed thereon and delivered thereto from the upper trays, or in accordance with the 100

amount of each liquid which would be on the tray at the particular temperature, if the liquids were completely miscible.

The overflow pipe 8 terminates at its lower end in a liquid seal cup 14 which may be above the liquid on the next tray below. Near its lower end the pipe 8 is provided with a branch pipe 16 which extends into the cup 14 only a comparatively short distance compared with the main pipe 8. A baffle 18 is placed above and over the outlet from the pipe 8 to the pipe 16 to prevent direct entry of the liquids thereinto. The function of the branch pipe 16 will be apparent when it is realized that in its absence the lighter of the two immiscible liquids entering the pipe 8 must accumulate in the lower end of the pipe until its weight is sufficient to overcome the height of heavier liquid in the cup, before it can be discharged around the lower end. Such operation would give irregular flow of the two liquids onto the trays and cause the backing up of lighter liquid in the overflow pipes. With the branch pipe 16 however, the lighter liquid can be regularly discharged through a shallow seal and thus avoid the difficulties mentioned.

If desired the pipe 8 and branch pipe 16 may seal directly in the liquids on the tray onto which they discharge, but the cup 14 has a distinct advantage in case of siphoning of tray liquid through the bubble caps, which would unseal the overflow pipes and thus give a bypass for vapors until sufficient condensate had been formed to make a seal.

In order to secure good stratification of the liquids on each tray and prevent excessive agitation near the overflow mechanism a metal screen 20 may completely surround the overflow 8 and band 10. This screen is preferably spaced from the band 10 and extended above the liquid level on the tray.

Fig. 3 represents a modified overflow apparatus in which an overflow pipe 22 discharges the lighter liquid while a second pipe 24 provided with a vented cap 26 is arranged to discharge the heavier liquid and still maintain a considerable quantity of light liquid on the tray. Means for adjusting the relative heights of the pipes 22 and 24 while not shown may take the form of a threaded sleeve on one of the pipes and the discharge end of pipe 22 may have a seal comparable to the branch 16 in Fig. 1.

Fig. 4 shows a further modification of the overflow mechanism in which the upper end of the pipe 8 is provided with a branch line 28 adapted to discharge the heavier liquid into the pipe 8 at a selected point below the upper edge of the pipe 8 over which the lighter liquid flows.

Fig. 5 shows the apparatus of the present invention applied to a complete bubble tower 30. In this figure is shown the apparatus according to the modification illustrated in Fig.

3, but it is to be understood that any of the various modifications according to the present invention may be applied in a similar manner. Fig. 5 also shows a screen 32 which operates substantially as screen 20 of Fig. 1. Such a screen may be used with any of the modifications shown.

The form of the column whether circular or rectangular in cross section is unimportant to the present invention, but where a long wier overflow extends across the side of a column, a vertically adjustable plate or dam may be placed in front of the wier to maintain the level of the lighter liquid in the same manner as the band 10.

The term "liquid" as used in the specification and claims is not to be understood as limited to a single chemical compound but may comprise a mixture of different substances forming a single layer. Thus in the rectification of secondary butyl alcohol water mixtures, some of the trays of the column will contain an upper liquid layer of secondary butyl alcohol and a lower liquid layer of water and butyl alcohol to the limit of its solubility in water under the conditions.

The drawings showing the various forms of the invention are merely diagrammatic and therefore no attempt is made to accurately proportion the various elements.

Having described the invention in its preferred form what is claimed as new is:

1. A vapor rectifying column, comprising a plurality of vertically spaced bubbler trays, a liquid overflow pipe projecting above each tray, for retaining a layer of condensate thereon and for conducting relatively heavy condensate therefrom onto the next lower tray, and a vertically adjustable overflow band spaced from, surrounding and projecting above the upper projecting end of said overflow pipe for maintaining a higher level of relatively light condensate on each tray.

2. A vapor rectifying column, comprising a plurality of vertically spaced bubbler trays, a liquid overflow pipe for each tray, the upper end of which projects above the tray, for maintaining a body of condensate thereon, means for maintaining a liquid seal for the lower end of each pipe, a vertically adjustable band surrounding and projecting above the upper projecting end of said pipe, and a branch pipe connecting with the lower portion of each overflow pipe and projecting into said liquid seal to a less extent than said overflow pipe.

3. In the art of rectifying vapors which condense to form at least two immiscible liquid condensates, the improvement which comprises passing the vapors through bodies of condensate maintained in separate zones at different levels, maintaining portions of each condensate in the zones in which they would exist as liquid at the particular temperatures on the zones, and in substantially the pro-

portions in which they would be present if the condensates were completely miscible, and overflowing portions of each condensate from one zone to the next lower zone counter to the flow of vapors through said zones.

- 5 4. In a bubbler tray column, a bubbler tray, a condensate overflow apparatus therefor, comprising an overflow at one level for a heavy liquid, an overflow for a lighter liquid at a higher level, and means for preventing the direct entry of lighter liquid into said first mentioned overflow at the overflow level for the heavy liquid.
- 10 5. In a bubbler tray column, a bubbler tray, a condensate overflow apparatus therefor, comprising an overflow at one level for a heavy liquid, an overflow for a lighter liquid at a higher level, means for preventing the direct entry of lighter liquid into said first mentioned overflow at the overflow level for the heavy liquid, and a screen surrounding said overflow apparatus for maintaining the liquids in a relatively quiescent state.
